AIR RELEASE DEVICE FOR HUMIDIFIERS
AND THE LIKE

Edward S. Cornell, Jr., Larchmont, N. Y.

Application March 25, 1933, Serial No. 662,723

2 Claims. (Cl. 219—38)

This invention relates to pressure valve attachments.

In my copending application entitled Humidifying device, filed February 28th, 1933, bearing

Serial No. 658,901, I have described and claimed a humidifier cooperating with a radiator heating system of the regulation or other approved hot water, steam or other suitable type, comprising in general a hollow heating element arranged to be connected with the interior, specifically the interior of an end radiator unit, of a regulation radiator, a casing for containing water in heat exchange contact with the hollow heating element, and other appurtenant parts.

16 The present invention comprises means of general hollow construction arranged to be interposed between the interior of the radiator and the hollow heating element, particularly for a radiator or heating system employing steam or 20 equivalent as the heating medium, the same including or providing for the connection therewith of an air valve for automatic venting purposes.

25 My invention is applicable with the employment of devices other than humidifiers in connection with a radiator or equivalent heating unit.

More particularly, my invention is directed to a member, advantageously a casting, comprising 30 at one side a nipple element, preferably threaded and adapted to be connected with the usual threaded opening leading to the interior of a radiator unit, and further comprising an opening for the reception of a regulation or other approved air valve, and further comprising a nipple element for a direct connection with or indirect connection through piping leading to one end of a hollow heating element or other hollow element of a device communicatively associated with the 35 radiator.

40 Further features and objects of my invention will be more fully understood from the following detail description and the accompanying drawings, in which

45 Fig. 1 is a side elevation of a preferred embodiment of my invention, illustrated in operative connection with an end unit of a radiator, partially illustrated, and a humidifier, the last-named being illustrated in central vertical section;

50 Fig. 2 is a vertical sectional elevation on line 2—2 of Fig. 1, on an enlarged scale; and

Fig. 3 is a sectional elevation on line 3—3 of Fig. 2.

55 Referring to the drawings, the radiator is in-

dicated generally by the reference number 10; the end unit thereof is indicated 11. At 12, 13 are indicated the regulation threaded openings of a regulation radiator unit.

The humidifier 14 typical of a device communicatively associated with the radiator, as illustrated, comprises a hollow heating element 15, illustrated in the form of a section of a fin tubing, the lower end of which is connected to a header 16, preferably having a threaded nipple 60 or other suitable termination 17 arranged for connection, as by means of tubing 18 and pressure couplings 19, 20, for communication with the interior of a radiator 10, or unit thereof 11; as shown in Fig. 1 the communication is effected 65 through the attachment means 21, described more fully hereinafter.

The upper portion of the heating element 15 is shown provided with a header 22 having a threaded nipple or other suitable termination 23 70 arranged for communicative connection with the interior of a radiator 10, or unit thereof 11, as by means of piping 24 and pressure couplings 25, 26, supplemented if desirable or necessary with the reversely threaded nipple 27.

75 More particularly, the embodiment of my attachment means, see Figs. 1, 2 and 3, comprises a hollow body 30, shown in the form of a casting, having at its one vertical face a threaded nipple or other suitable termination 31, preferably integral therewith, arranged to be threadedly connected in the opening 12 of the end radiator unit 11. The body 30 is also provided with the threaded opening 32, or equivalent, for suitable connection with the illustrated lower end of the piping 90 18, namely, by means of a threaded nipple 33.

80 The body 30 is further provided with a threaded or other suitable opening 34 attachment to receive the threaded nipple or other suitable termination 35 of a regulation or other suitable automatic air 90 venting valve 36.

85 The configuration of the hollow body 30 is shown particularly designed for cooperating with a drain tubing 37 of a regulation air release valve 36, and it is understood that the body 30 may be 100 varied in configuration and detail construction to accord with the assembly of any particular air release valve or equivalent device employed therewith.

105 Advantageously, the nipples 31, 32 are positioned on opposite faces of the body 30 and the opening 34 on a face lateral in common to such opposite faces. Specifically, as illustrated, such laterally common face is substantially at right angles to such opposite faces, thereby enabling 110

the air release valve 36 to be placed in or removed from position by rotative movement, without encountering obstruction either by engagement with the radiator unit 11 or the humidifier or 5 otherwise.

As appears, the vertical dimension of the interior of the body 30 is designed in general to accommodate the drain tube 37 of the illustrated air release valve 36, such drain tube 37 usually 10 depending freely from the threaded nipple portion 35. Accordingly, upon rotation of the body of the air release valve 36 in placing in position or removing from position relative to the threaded opening 34, the drain tube 37 is accommodated within the interior of the hollow body 30.

The nipple 31, in fulfilling its function of drainage by gravity, is advantageously located at substantially the lowermost position with respect to the interior of the hollow body 30, to effect discharge under gravity of liquid formed under condensation or otherwise from the interior of the body 30.

In the employment of my invention, citing the instance of the use of a humidifier as representative of a device communicatively associated with the radiator and the use of steam as the heating medium, under the condition of generation of steam and its conveyance through the heating system inclusive of the indicated radiator 10, 25 steam enters the nipple 31 within the body 30, thence through the nipple 33, piping 18, nipple 17, lower header 16, into the heater element 15, and, possibly, also through the upper header 22, piping 24, in return to the interior of the radiator 10, whereby water 40 placed within the casting 14 of the humidifier is evaporated by the heat units exchanged through the intermediation of the heater element 15. Water resulting from the condensation of steam in the heater element 15, 30 flows under gravity into the lower header 16, piping 18, thence within and through the hollow interior of the body 30, and ultimately through the nipple 31 into the radiator 10 and the piping connected therewith. Automatic venting of any air entrapped within the above stated parts is effected by the regulation or other approved automatic air vent device 36, any liquid condensed within the air vent device 36 discharging through its tube element 37 into the interior of the hollow body 30 and thus through the nipple 31.

Whereas I have described my invention by reference to specific forms thereof, it will be under-

stood that many changes and modifications may be made without departing from the spirit of the invention.

I claim.

1. An air release device for an associated heating radiator and a therewith connected humidifier provided with a heater unit, the air release device comprising a hollow body provided with a nipple portion communicating with a lower portion of the interior of the hollow body, the said nipple portion being arranged to be connected with the radiator through a port in the radiator, said air release device further comprising an opening arranged for connection with an air release valve communicating with the interior of the device at a location above the stated region of communication of said lowerly disposed nipple portion, the air release device further comprising an opening communicating with the interior of its hollow body at a location above the stated region of communication of said lowerly disposed nipple portion, said second named opening being arranged for connection and communication with a lowerly portion of the heater element of the humidifier, the upper portion of the heater element of the humidifier being connected with the interior of the radiator. 80 85 90 95 100

2. An air release device for an associated heating radiator and a therewith connected humidifier provided with a heater unit, the air release device comprising a hollow body provided with a nipple portion communicating with a lower portion of the interior of the hollow body, the said nipple portion being arranged to be connected with the radiator through a port in the radiator, said air release device further comprising an opening arranged for connection with an air release valve communicating with the interior of the device at a location above the stated region of communication of said lowerly disposed nipple portion, the air release device further comprising an opening communicating with the interior of its hollow body at a region above the stated region of communication of said lowerly disposed nipple portion and below the stated region of communication of said first named opening, said second named opening being arranged for connection and communication with a lowerly portion of the heater element of the humidifier, the upper portion of the heater element of the humidifier being connected with the interior of the radiator. 105 110 115 120 125 130 135 140 145 150
